(57) **CLAIM**

The ornamental design for a bedpan, as shown and described.

DESCRIPTION

FIG. 1 is a top rear perspective view of a bedpan;
FIG. 2 is a bottom front perspective view thereof;
FIG. 3 is a right side view thereof, the left side view being a mirror image thereof;
FIG. 4 is a front view thereof;
FIG. 5 is a rear view thereof;
FIG. 6 is a top view thereof;
FIG. 7 is a bottom view thereof; and,
FIG. 8 is a perspective view of the bedpan shown in FIG. 1 having a hygienic bag mounted thereto.

The parts shown in broken lines are environmental only and form no part of the claimed design.
